UNITED STATES PATENT OFFICE.

SAMUEL HUSE, OF NEW YORK, N. Y.

SHIP'S CAPSTAN.

Specification of Letters Patent No. 17,969, dated August 11, 1857.

To all whom it may concern:

Be it known that I, SAMUEL HUSE, of the city and State of New York, have invented certain new and useful Improvements in 5 Capstans, producing what may be designated as a "Power-Capstan;" and I do hereby declare that the following is a full and exact description thereof, reference being had to the accompanying drawings and 10 to the letters of reference marked thereon.

The nature of my improvement or invention consists in so constructing a capstan, that it can be made to have a rapid or quick action, in cases where but little power is 15 required, or but little resistance is to be overcome,—or a slower and more powerful action, when great power is required or great resistance is to be overcome by simply raising or lowering a couple or series of 20 straight levers or bars, which can be done instantly, and without stopping the action of the capstan, or changing the motion of any part of it, the capstan also being capable of working equally well, whichever way 25 it is turned, turning either way as desired.

Figure 1 is a perspective view of the capstan; Fig. 2 is a sectional view, vertically through the middle; Fig. 3 is a view of the underside of the drum or head; Fig. 4 is a 30 view of the bottom of the barrel; Fig. 5 is a view of the bottom of the capstan, the barrel removed, showing the mechanism; Fig. 6 is a view of the movable plate and its cog wheel, at the bottom of the capstan, and 35 Fig. 7 is a sectional view of Fig. 6 showing the manner of fastening the cog wheel.

The capstan consists of a drum head *a*, and barrel *B*, separate from each other, and moving irrespective of each other. Through 40 the center passes a shaft or standard *C*, firmly fastened to the foundation *O*, and about which the capstan revolves. Around the standard *C*, is a hollow metallic shaft, or cylinder *D*, working or turning in an 45 other hollow shaft, placed in the center of the barrel *B* and having firmly attached to its lower end a cog wheel *E*, and fastened itself to the drumhead *A*, so that the cylinder *D* and its wheel *E* move or turn with *A*. At 50 the bottom of the barrel *B*, and within a recess provided for it, I place a movable plate *G*, to the under side of which is attached a cogwheel *H*, which meshes into the cogwheel *E* fastened to cylinder *D*, and also

in the cogs *I*, which are upon the foundation *O*, as shown in Fig. 5. The object and action of this plate and its cogwheel will be explained hereafter.

Through the barrel *B* of the capstan, I pass two or more straight bars or levers 60 *L*, *L*, which can be raised or lowered by the crank or handle *M*, or any convenient mechanical arrangement, on the outside of the capstan. These bars are of such a length, that when raised, they will enter the drumhead *A*, in cavities designed for that purpose and shown in Fig. 3, and will be clear of the plate *G*, and when lowered they will be clear of the drumhead *A*, and pass into or through the plate *G*, in cavities shown in 70 Fig. 6. In Fig. 2, these bars are shown, as being lowered. When these bars are raised, they connect the head and barrel of the capstan, so that they turn together and as one piece: when however they are lowered they 75 connect the barrel with the plate *G*, and then these move together. When these bars are raised the action of the capstan will be as follows, *i. e.* the barrel and drumhead 80 will move together, and of course as rapid a motion may be given to the barrel as can be given to the drumhead *A*, and the plate *G*, being free to move turns as rapidly as *D*, and *E*. This gives a quick action to the barrel *B*, such as is required when but little 85 power is required, or little resistance to be overcome. If however we turn the handle *M*, and lower these bars, the whole action of the capstan is at once changed. The drumhead *A*, turns independently of the 90 barrel *B*, carrying with it however the cylinder *D* and cogwheel *E*. This cogwheel *E*, meshing into the cogwheel *H*, on the under side of *G*, moves the plate *G*, and with it the barrel *B*, these two, the plate *G* 95 and barrel *B* being connected together, or made as one, by the bars *L*, *L*, dropping through *G*,—and the wheel *H*, in turn meshes into *I*. A much slower motion is thus given *B*, than is imparted to *A*, and by the cogwheels *E*, and *H*, and *I*, power is greatly increased, in the proportion of the radius of *E*, and of *I*,—an arrangement very desirable when great resistance is to be overcome. As this change from quick to slower 100 motion, and from less to greater power is effected by means of cogwheels, as above described, which are thrown into or out of 105

action, by the raising or lowering of the bars L, L, it is plain that the capstan will work or turn either way, as may be desired or convenient, and will work in one direction 5 as well as the other.

By varying the size of the cog wheel gearing, the motion of the barrel B, may be increased or diminished, or the power used at better advantage.

10 Fig. 8, shows a method of varying the gearing so as to much increase the power, while the velocity of the barrel remains the same. The cog wheel H, is a double wheel, the lower one H', being much smaller than 15 H. H', meshes into I, which has consequently to be brought somewhat nearer the center—or in other words the radius of I, is somewhat shortened—as will be seen by Fig. 9. The power however is much increased. Fig. 7, shows the connection of 20 the single wheel H, with G; and Fig. 10, shows the connection of the double wheel with the same plate.

As will be apparent the method of arrangement of the cogwheels may be varied, 25 and the general character and feature of the capstan remain unchanged.

By any arrangement and principle of construction therefore, I produced a capstan, 30 which can be worked rapidly and with less power, or more slowly, and with greatly increased power, according to circumstances, by simply raising or dropping two or more clutch bars, which can be done instantaneously, without any interference with the 35 continued action of the capstan, and without any change in the manner or direction of the working of any of its parts, and

which can be worked or turned either way, 40 as desired.

The great convenience and use of a capstan with variable velocity and power, and which can be worked in either direction need not be specified.

I am aware that capstans have been 45 arranged to give a more rapid motion or one with increased power, by connecting or disconnecting the drum and barrel and at the same time throwing into play or out of play internal gearing, or by changing the 50 direction of motion of the drum and barrel, and therefore do not claim generally the construction of a capstan to accomplish these ends. But

What I claim as my invention and desire 55 to secure by Letters Patent is—

1. The arrangement and use of the hollow shaft D, attached at one end to the drum or head, and in combination therewith the movable gear plate G, constructed substantially as described and worked by a pinion on the lower end of D. 60

2. I claim also in combination with such hollow shaft and movable gear plate the arrangement of the clutch levers, or an equivalent thereof, for the purpose of connecting such movable gear plate to the barrel and at the same time disconnecting the head and barrel, or vice versa, thus changing the action of the capstan to a quicker, or more 65 powerful one, in a moment and without changing its motion, or displacing any gear. 70
